SIGNALING SYSTEM

Clarence E. Lomax, Oak Park, and Charles F. Ffolliott, Wheaton, Ill., assignors to Associated Electric Laboratories, Inc., Chicago, Ill., a corporation of Delaware

Application May 4, 1939, Serial No. 271,696

12 Claims.

(Cl. 179—5)

The present invention relates to signaling system and, more particularly, to improvements in combination alarm and telephone systems of the general character disclosed in Ffolliott Patent No. 5 2,122,460, granted July 5, 1938.

In a signaling system of this type, a number of combination alarm and telephone stations are associated with an operator position by a number of lines respectively extending therebetween. 10 Telephone apparatus is provided at each of the stations and answering apparatus is provided at the operator position in order to facilitate the establishment of connections between the stations and the operator position. Furthermore, apparatus is provided at each of the stations which is selectively operative to initiate a telephone call or an alarm on the line extending to the station, whereupon corresponding signals identifying the line and the telephone call or alarm initiated 15 thereon are transmitted to the operator position. Also, alarm recording equipment is usually provided at the operator position which is operative automatically to record the code of a line having an alarm thereon, thereby to identify the line.

It is an object of the present invention to provide, in a signaling system of the general character just described, improved and exceedingly simple apparatus for establishing connections between the combination alarm and telephone stations and the operator position.

Another object of the invention is to provide, in a signaling system of the type described, an improved and exceedingly simple arrangement for initiating telephone calls and alarms on the combination alarm and telephone lines and for controlling the transmission of corresponding signals to the operator position.

A further object of the invention is to provide, in a signaling system of the type described, an improved and exceedingly simple arrangement for recording the code of a line having an alarm thereon, thereby to identify the line.

A further object of the invention is to provide, in a signaling system of the type described, an improved correcting circuit adapted to be utilized in conjunction with a line having a ground fault thereon, in order to render the line usable notwithstanding the ground fault thereon, and which embodies an arrangement for controlling the transmission of corresponding signals to the operator position when telephone calls and alarms are initiated on the associated line.

The features of the present invention are illustrated as being incorporated in a signaling system including a number of combination alarm and telephone stations, an operator position and a number of lines respectively extending between the stations and the operator position. Telephone apparatus is provided at each of the stations; and answering apparatus is provided at the

operator position. A line circuit is individually associated with each of the lines; and the line conductors of each of the lines are connected to a source of current.

In accordance with one feature of the invention, an enclosing casing having a door is provided at each of the stations; and the telephone apparatus at the station is housed in the enclosing casing. The telephone apparatus comprises a repeater provided with first and second windings, a first telephone instrument of the sound powered type and operatively associated with the first winding of the repeater, and a second telephone instrument of the common battery type and normally operatively disassociated from the line. Also, a resistor is provided at the station, the resistor and the second winding of the repeater being normally connected in series circuit relationship in the line, and the resistance of the resistor being so proportioned that the repeater is normally effectively deenergized. A first switch is provided at the station which is operative to reduce the effective resistance of the resistor, thereby effectively to energize the second winding of the repeater in order to initiate a telephone call on the line. Also, a second switch is provided at the station which is operative to interrupt the line, thereby to initiate an alarm on the line. Finally a hookswitch is provided at the station which is operative to short-circuit the second winding of the repeater and operatively to associate the second telephone instrument with the line.

In accordance with another feature of the invention, each of the line circuits comprises a control arrangement including first and second relays, the first and second relays and the resistor at the associated station being connected in series circuit relationship with the corresponding line. The first and second relays are so connected and arranged that the first relay is normally operated and the second relay is normally restored, the second relay being operated when the effective resistance of the resistor at the associated station is reduced, and the first relay being restored when the line is interrupted. A signaling arrangement is associated with the line circuit which is responsive to the restoration of the first relay or the operation of the second relay for transmitting a first signal to the operator position, and responsive to the restoration of the first relay following the operation of the second relay for transmitting a second signal to the operator position. Also, it is noted that the control arrangement provided in the line circuit is responsive to the presence of an alarm on the corresponding line when the line circuit is associated therewith for controlling the alarm recording equipment, thereby to cause the line to be identified.

In accordance with a further feature of the invention, a correcting circuit is provided which is adapted to be associated with any one of the lines having a ground fault thereon, thereby to render the faulty line usable notwithstanding the ground fault thereon. Also, means is provided which is controlled from the operator position for disassociating the corresponding line circuit from the faulty line and for associating the correcting circuit therewith. Furthermore, a control arrangement is provided in the correcting circuit which is responsive to the presence of a telephone call on the faulty line when the correcting circuit is associated therewith for transmitting a first signal to the operator position, and responsive to the presence of an alarm on the faulty line when the correcting circuit is associated therewith for transmitting a second signal to the operator position. Also, it is noted that the control arrangement provided in the correcting circuit is responsive to the presence of an alarm on the faulty line when the correcting circuit is associated therewith for controlling the alarm recording equipment, thereby to cause the line to be identified.

Further features of the invention pertain to the particular arrangement of the circuit elements thereof, whereby the above-outlined and additional features are attained.

30 The novel features believed to be characteristic of the invention are set forth with particularity in the appended claims. The invention, both as to its organization and method of operation, together with further objects and advantages thereof, will best be understood by reference to the following specification taken in connection with the accompanying drawings, in which Figures 1 to 4, inclusive, taken together, illustrate diagrammatically the details of a signaling system embodying the present invention.

Referring now more particularly to Figs. 1 to 4, inclusive, of the drawings, the signaling system there illustrated comprises a central office provided with an operator position 60 of the manual type, a number of combination alarm and telephone stations including the station 50, and a number of telephone substations, including the substation C. Each of the combination alarm and telephone stations is connected to the central office by a combination alarm and telephone line extending therebetween and terminates in a corresponding jack at the operator position 60, the combination alarm and telephone station 50 being connected to the central office by the line 100 extending therebetween and terminating in the jack J120 at the operator position 60. Similarly, each of the telephone substations is connected to the central office by a telephone line extending therebetween and terminating in a corresponding jack at the operator position 60, the telephone substation C being connected to the central office by the line 450 extending therebetween and terminating in the jack J445 at the operator position 60. More specifically, the central office may have an ultimate capacity of several thousand combination alarm and telephone lines and several hundred telephone lines, the combination alarm and telephone lines being arranged in groups of 200 lines each. A line circuit 65 is individually associated with each of the combination alarm and telephone lines, the line circuit 180 shown in Fig. 1 being individually associated with the line 100; and a line circuit of any desired type is individually associated with each of the telephone lines, the line circuit 448 being

individually associated with the telephone line 450. The operator position 60 comprises a number of correcting circuits, including the correcting circuit 245 shown in Fig. 2, a number of patching cords, including the patching cord 231 shown in Fig. 2A, a test circuit 200 shown in Fig. 2B, and position apparatus 400 shown in Fig. 4.

Furthermore, the central office comprises alarm recording equipment 300, shown in Fig. 3, which includes a number of finder switches 10 301, 302, 303, etc., a finder sequence switch 304, a sender switch 305, a sender sequence switch 306 and a recorder 307.

The alarm recording equipment 300 is of the type of that disclosed in Clarence E. Lomax and John H. Voss Patent No. 2,121,159, granted June 21, 1938, and is connected and arranged in a similar manner. More particularly, each of the finder switches 301, 302, etc., is of the 200 point type and corresponds to an associated group of 200 lines; the finder sequence switch 304 is operative to select one of the finder switches corresponding to a group of 200 lines including a particular line having an alarm thereon; the sender switch 305 is operative to transmit an impulse code to the recorder 307 identifying the particular line; the recorder 307 is operative to print a record of the code transmitted thereto; and the sender sequence switch 306 is operative to control the number of repetitions of the code transmitted and thereafter to release the alarm recording equipment 300.

Preferably, the apparatus provided at each combination alarm and telephone station is identical to that provided at the station 50 which comprises a telephone instrument A of the common battery type, a telephone instrument B of the magnetic or sound powered type, a ringer, not shown, a repeater 105, a hookswitch S110, an alarm switch S115, and a door switch S113. 40 It is noted that this apparatus at the combination alarm and telephone station 50 is housed in a suitable enclosing casing indicated at 51, which is provided with a pivotally mounted door 52 operatively associated with the door switch S113 in a 45 manner more fully described subsequently. Further, it is noted that the telephone instrument A comprises a transmitter and a receiver, the receiver cooperating with the hookswitch S110; while the telephone instrument B comprises a 50 single transmitter and receiver unit. Furthermore, each of the telephone substations is provided with apparatus including a telephone instrument of the common battery type and a ringer.

Preferably, each of the line circuits individually associated with the combination alarm and telephone lines is identical to the line circuit 180 individually associated with the line 100 which comprises a line relay R140, an impulse relay 60 R145, an answer relay R130, and a number of control relays R150, R160, R185 and R190. Furthermore, it is noted that the line circuit 180 controls a supervisory lamp L174 associated with the jack J120 at the operator position 60.

Preferably, each of the patching cords is identical to the patching cord 231 and each of the correcting circuits is identical to the correcting circuit 245. The patching cord 231 comprises two plugs P235 and P240 connected together by three conductors C232, C233 and C234; while the correcting circuit 245 comprises two jacks J245 and J251, and a number of control relays R260, R265, R270, R275, R280 and R290. Also, a supervisory lamp L256 arranged at the operator position 60 is 75

individually associated with the correcting circuit 245.

The test circuit 200 comprises an ammeter 206, a plug P201 and a number of keys K207, K210 and K215, and it is utilized to test the combination alarm and telephone lines for open circuit, short circuit and ground circuit faults thereon in a manner more fully described subsequently.

The operator position apparatus 400 arranged 10 at the operator position 60 comprises a receiver 453, a transmitter 454, a receiver amplifier 475, a transmitter amplifier 476, a number of repeaters 410, 490 and 495, and a cord circuit including two plugs P401 and P440, two ringing keys K405 and K430, and two battery supply relays R426 and R427. Further, the operator position apparatus 15 400 comprises two keys K415 and K420, a supervisory lamp L419, an audible alarm 444, and a number of control relays R435, R455, R458, R460, 20 R465, R470 and R480.

A better understanding of the connection and arrangement of the apparatus incorporated in the signaling system will be facilitated from a consideration of the operation thereof incident to 25 the initiation of telephone calls and alarms at the combination alarm and telephone stations.

The line circuit individually associated with each of the combination alarm and telephone lines is normally partially operated. For example, in the line circuit 180 individually associated with the combination alarm and telephone line 100 the impulse relay R145 is normally operated while the line relay R140 is normally energized but in a restored position, due to the fact 30 that the last-mentioned relay is of the marginal type. The circuit for energizing the windings of the line and impulse relays R140 and R145, respectively, extends from ground by way of the upper winding of R145, C175, the contacts 131, 35 the line conductor C101 of the line 100, the contact 112 of the hookswitch S110, the winding 107 of the repeater 105, the resistor 108, the contacts 116 of the alarm switch S115, the line conductor C102 of the line 100, the contacts 132, the winding 40 of R140 and the lower winding of R145 to battery. As previously noted, the impulse relay R145 is normally operated, thereby to retain interrupted at the contacts 146 a circuit, traced 45 hereinafter, for energizing the winding of the control relay R160; and the line relay R140 is not operated due to the high series resistance of the above-traced circuit, the resistance of this circuit residing principally in the resistor 108.

In order to initiate a telephone call at one of 50 the combination alarm and telephone stations, it is only necessary to open the door of the enclosing casing thereof. For example, in order to initiate a telephone call at the combination alarm and telephone station 50, the door 52 of the enclosing casing 51 thereat is opened, thereby to cause the door switch S113 to be operated. More particularly, the contacts 114 of the door switch S113 are operated into engagement, thereby to complete an obvious path for short-circuiting the 55 resistor 108. When the resistor 108 is thus short-circuited, the resistance of the previously traced series circuit for energizing the winding of the line relay R140 is substantially reduced, thereby to cause the current traversing this circuit to be 60 substantially increased, whereupon the line relay R140 operates shortly thereafter, this relay being of the slow-to-operate type. Upon operating, the line relay R140 completes, at the contacts 141, an obvious circuit for energizing the winding of the 65 control relay R150, thereby to cause the lat-

ter relay to operate. Upon operating, the relay R150 completes, at the contacts 151, a holding circuit for energizing the winding thereof, this circuit extending from ground by way of the contacts 134, the contacts 151, and the winding of R150 to battery. Also, upon operating, the relay R150 prepares at the contacts 152 a further point in the previously mentioned circuit for energizing the winding of the control relay R160, 10 interrupts at the contacts 153 a point in a circuit, traced hereinafter, for illuminating the lamp L114 associated with the jack J120 at the operator position 60, and completes at the contacts 154 an alternative circuit for illuminating the supervisory lamp L174. The last-mentioned circuit 15 extends from ground by way of the contacts 154, the contacts 163 and the lamp L174 to battery.

The steady illumination of the supervisory lamp L174 associated with the jack J120 at the operator position 60 indicates to the operator thereat that 20

a telephone call has been initiated on the combination alarm and telephone line 100 extending to the combination alarm and telephone station 50 and terminated by the jack J120. The call on the line 100 is answered by the operator at 25 the operator position 60 upon inserting the plug P401 of the cord circuit included in the operator position apparatus 400 into the jack J120 and upon operating the key K420 to its off-normal position. When the plug P401 is inserted into the 30 jack J120 and the key K420 is operated away from its normal position, a connection is completed between the repeater 105 at the combination alarm and telephone station 50 and the repeater 410 included in the operator position apparatus 400 at the operator position 60. The last-mentioned connection extends from the upper terminal of the winding 107 of the repeater 105 by way of the contacts 112 of the hookswitch S110, C101, the jack tip 121, the plug tip 402, 35 the contacts 406 of the ringing key K405, the contacts 421 of the key K420, the winding 412 of the repeater 410, the condenser 413, the winding 414 of the repeater 410, the contacts 422 of the key K420, the contacts 403 of the ringing 40 key K405, the plug ring 403, the jack ring 122, C102, the contacts 116 of the alarm switch S115 and the contacts 114 of the door switch S113 to the lower terminal of the winding 107. At this 45 time the windings 106 and 107 of the repeater 105 are operatively coupled and the windings 412, 414 and 411 of the repeater 410 are operatively coupled, the winding 106 of the repeater 105 being included in an obvious operating circuit for the telephone instrument B, and the winding 411 50 of the repeater 410 being included in an input circuit for the receiver amplifier 475. The input circuit for the receiver amplifier 475 extends from one terminal of the amplifier 475 by way of the contacts 471, the contacts 461, the winding 411 55 of the repeater 410, the contacts 464 and the contacts 473 to the other terminal of the amplifier 475. The receiver 453 at the operator position 60 is included in the output circuit of the receiver amplifier 475, this circuit extending from one terminal of the amplifier 475 by way of the contacts 481, the jack J475, the plug P476, the receiver 453, the plug P476, the jack J475 and the contacts 483 to the other terminal of the amplifier 475. 60

Also, when the key K420 is operated away from its normal position, the input circuit of the transmitter amplifier 476 is completed, this circuit extending from ground by way of the contacts 423 of the key K420 and the contacts 487 to one ter- 65

5 minal of the amplifier 476 and from the other terminal of the amplifier 476 by way of the contacts 485, the jack J477, the plug P478, the transmitter 454, the plug P478, the jack J477, and the winding of R458 to battery. The output circuit of the transmitter amplifier 476 includes the windings 492 and 494 of the repeater 490 and extends from one terminal of the amplifier 476 by way of the windings 492 and 494 to the other terminal of the amplifier 476. At this time, the telephone instrument B at the combination alarm and telephone station 50 is operatively associated with the receiver 453 at the operator position 60 and signal currents induced in the telephone instrument B when the party thereat speaks into the telephone instrument B will be transmitted to the receiver amplifier 475 and there amplified and conducted to the receiver 453.

20 When the operator at the operator position 60 speaks into the transmitter 454, undulating signal currents traverse an alternative path included in the input circuit of the transmitter amplifier 476, this path extending from one terminal of the amplifier 476 by way of the contacts 487, the condenser 475, the jack J477, the plug P478, the transmitter 454, the plug P478, the jack J477, and the contacts 485 to the other terminal of the amplifier 476. The undulating signal currents traversing the input circuit of the transmitter amplifier 476 are amplified and transmitted over the output circuit thereof, thereby to cause undulating voltages to be induced in the winding 493 of the repeater 490 operatively coupled with the winding 494 thereof included in the output circuit of the transmitter amplifier 476. The undulating voltages generated in the winding 493 of the repeater 490 cause undulating currents to flow in the circuit of the full-wave rectifier network 467 in an obvious manner, thereby to cause a full-wave rectifier current to traverse the winding of the control relay R465 in an obvious manner. When thus energized, the relay R465 operates to complete at the contacts 466 an obvious circuit for energizing the control relay R460, thereby to cause the latter relay to operate. Upon operating, the relay R460 interrupts at the contacts 461 and at the contacts 464 points in the previously traced circuit for connecting the winding 411 of the repeater 410 in the input circuit of the receiver amplifier 475 and completes at the contacts 462 and at the contacts 463 a circuit for connecting the winding 411 of the repeater 410 to the winding 491 of the repeater 490. The last-mentioned circuit extends from the upper terminal of the winding 411 by way of the contacts 462, the winding 491 and the contacts 463 to the lower terminal of the winding 411. At this time the windings 491 and 492 of the repeater 490 are operatively coupled, thereby to cause the amplified undulating currents to be induced in the winding 491 of the repeater 490.

25 Each time the operator at the operator position 60 speaks into the transmitter 454, the control relay R460 operates in the above-described manner, thereby operatively to connect the winding 411 of the repeater 410 to the winding 491 of the repeater 490 in order to cause signal currents to be transmitted from the transmitter 454 to the telephone instrument B in an obvious manner. Each time the operator at the operator position 60 listens, the control relay R460 restores, thereby operatively to connect the winding 411 of the repeater 410 to the input circuit of the receiver amplifier 475 in order to cause signal

30 currents to be transmitted from the telephone instrument B to the receiver 453 in an obvious manner.

35 It is contemplated that the party at the combination alarm and telephone station 50 will utilize the sound powered telephone instrument B thereat in conversing with the operator at the operator position 60. However, the party at the station 50 may utilize the common battery telephone instrument A at the station 50. In any case, the common battery telephone instrument A is utilized by the party at the station 50 when the call is to be extended by the operator at the operator position 60 over a telephone line in a manner more fully described hereinafter. Assuming that the party at the combination alarm and telephone station 50 removes the receiver of the telephone instrument A from its switchhook, the hookswitch S110 is operated, thereby to interrupt at the contacts 112 thereof a point in the previously traced path for connecting the winding 107 of the repeater 105 to the line conductors C101 and C102 of the line 100 and to complete at the contacts 111 thereof a path for connecting the telephone instrument A across the line conductors C101 and C102 of the line 100. The last-mentioned path extends from the line conductor C101 by way of C103, the telephone instrument A, C104, the contacts 111 of the hookswitch S110, and the contacts 116 of the alarm switch S115 to the line conductor C102. At this time, talking battery is supplied to the telephone instrument A from the impulse relay R145 included in the line circuit 180, ground potential being connected to the line conductor C101 and battery potential being connected to the line conductor C102 by way of the windings of the impulse relay R145 and the line relay R140 as previously explained. Although a very feeble current traverses the telephone instrument A by way of the windings of the impulse relay R145 and the line relay R140, sufficient current traverses the telephone instrument A to control the receiver amplifier 475. Thus, the telephone instrument A at the combination alarm and telephone station 50 may be utilized to converse with the operator at the operator position 60.

40 A call which is to be extended from one of the combination alarm and telephone stations, such, for example, as the station 50, to one of the telephone substations, such, for example, as the substation C, is first initiated at the combination alarm and telephone station 50 and answered at the operator position 60 in the previously described manner, the telephone instrument B being utilized at the station 50 to converse with the operator at the operator position 60. The operator at the operator position 60 then advises the party at the combination alarm and telephone station 50 to remove the receiver of the telephone instrument A thereat from its switchhook, thereby to cause the telephone instrument A to be connected across the line conductors C101 and C102 of the combination alarm and telephone line 100 in the previously described manner. The operator at the operator position 60 then actuates the key K415 thereby to complete at the contacts 416 thereof a circuit for energizing the lower winding of the control relay R435, this circuit extending from ground by way of the lower winding of R435, the contacts 424 of the key K420 and the contacts 416 of the key K415 to battery. When energized over the above-traced circuit, the relay R435 operates to complete, at the contacts 438, a holding circuit for energizing the

upper winding thereof in series with the winding of the answer relay R130 in the line circuit 180 individually associated with the line 100. This circuit extends from ground by way of the upper winding of R435, the contacts 438, the plug sleeve 404, the jack sleeve 123, C176 and the winding of R130 to battery. When energized over the above-traced circuit, the answer relay R130 operates to interrupt, at the contacts 134, a point in the previously traced holding circuit for energizing the winding of the control relay R150 and completes, at the contacts 135, an obvious holding circuit for energizing the lower winding of the impulse relay R145. Also, the answer relay R130 interrupts, at the contacts 131 and at the contacts 132, the previously traced series circuit for energizing the windings of the line relay R140 and the impulse relay R145, thereby to clear the combination alarm and telephone line 191 of impedance elements. Further, the answer relay R130 completes, at the contacts 133, a circuit for energizing the winding of the line relay R140 in a reverse direction, this circuit extending from ground by way of the contacts 135, the winding of R140, the contacts 133 and the resistor 118 to battery. When the above-traced circuit is completed, the line relay R140 quickly restores and does not reoperate due to the high resistance of the resistor 118. Upon restoring, the line relay R140 interrupts, at the contacts 141, the previously traced original circuit for energizing the winding of the control relay R150, thereby to cause the latter relay to restore. Upon restoring, the relay R150 interrupts, at RA154, the previously traced circuit for steadily illuminating the supervisory lamp L174 associated with the jack J120 at the operator position 60. Also, upon operating, the answer relay R130 completes, at the contacts 136, an obvious circuit for energizing the control relay R190, which relay has no function to perform at this time. The answer relay R130, the impulse relay R145 and the control relay R190 occupy their operated positions and the remainder of the relays in the line circuit 180 occupy their restored positions at this time.

Also, upon operating, the control relay R435 completes, at the contacts 439, a series circuit for energizing the winding of the relay R455 and for illuminating the supervisory lamp L419, this circuit extending from ground by way of the contacts 439, the contacts 428, the lamp L419 and the winding of R455 to battery. When energized over the above-traced circuit, the control relay R455 operates to prepare, at the contacts 456, a circuit, traced hereinafter, for operating the alarm 444. The illumination of the supervisory lamp L419 gives the operator at the operator position 60 answer and disconnect supervision in connection with the called telephone line in a manner more fully described herein-after. Furthermore, the control relay R435 completes at the contacts 439 a series circuit for energizing the windings of the control relays R470 and R480, this circuit extending from ground by way of the contacts 439, the contacts 425 of the key K420, the winding of R470 and the winding of R480 to battery. When energized over the above-traced circuit, the relay R480 operates immediately, while the relay R470 operates shortly thereafter, the latter relay being of the slow-to-operate type. Upon operating, the relay R480 interrupts at the contacts 481 and at the contacts 483 the connection between the receiver 453 and the output circuit of the re-

ceiver amplifier 475, completes at the contacts 482 and at the contacts 484 an operative connection between the receiver 453 and the winding 496 of the repeater 495, interrupts at the contacts 485 and at the contacts 487 the connection between the transmitter 454 and the input circuit of the transmitter amplifier 476, and completes at the contacts 486 and at the contacts 488 an operative connection between the transmitter 454 and the windings 498 and 499 of the repeater 495. The circuit for operatively connecting the receiver 453 to the winding 496 of the repeater 495 extends from one terminal of the receiver 453 by way of the plug P476, the jack J475, the contacts 482, the winding 496, the condenser 468, the contacts 484, the jack J475 and the plug P476 to the other terminal of the receiver 453. The circuit for operatively connecting the transmitter 454 to the windings 498 and 499 of the repeater 495 extends from ground by way of the contacts 423 of the key K428, the contacts 488, the windings 499 and 498, the contacts 486, the jack J471, the plug P478, the transmitter 454, the plug P478, the jack J477 and the winding of R458 to battery.

Upon operating, the control relay R470 interrupts at the contacts 471 and at the contacts 473 the connection between the winding 411 of the repeater 410 and the input circuit of the receiver amplifier 475 and completes at the contacts 472 and at the contacts 474 a connection between the winding 411 of the repeater 410 and the windings 496 and 497 of the repeater 495. The last-mentioned connection extends from the upper terminal of the winding of R411 by way of the contacts 461, the contacts 472, the windings 496 and 497, the contacts 474, and the contacts 464 to the lower terminal of the winding 411.

Finally, upon operating, the control relay R435 completes, at the contacts 436 and 437, a loop circuit extending between the battery supply relay R426 and the telephone instrument A at the combination alarm and telephone station 50. This loop circuit extends from ground by way of the upper winding of R426, the contacts 436 and the contacts 406 of the ringing key K405 to the plug tip 402 and from battery by way of the lower winding of R426, the contacts 437 and the contacts 408 of the ringing key K405 to the plug ring 403, the plug tip 402 and the plug ring 403 being included in a circuit extending to the telephone instrument A at the station 50 as previously explained. Thus, at this time, the common battery telephone instrument A at the combination alarm and telephone station 50 is operatively associated with the receiver 453 and the transmitter 454 at the operator position 60 by way of the repeaters 410 and 495.

In order to extend the call to the telephone substation C, the operator at the operator position 60 inserts the plug P440 of the cord circuit included in the operator position apparatus 400 into the jack J445 individually associated with the telephone line 450 and then operates the ringing key K430 away from its normal position, thereby to cause ringing current to be projected over the telephone line 450 to the telephone substation C. The circuit for projecting ringing current to the telephone substation C extends from one terminal of a source of alternating current supply by way of the contacts 432 of the ringing key K430, the plug tip 441, the jack tip 446 and the line circuit 449 to the line conductor C451 of the telephone line 450 and from the other

- terminal of the source of alternating current supply by way of the contacts 434 of the ringing key K430, the plug ring 442, the jack ring 441 and the line circuit 449 to the line conductor 5 C452 of the telephone line 450, the ringer at the telephone substation C being bridged across the line conductors C451 and C452. The operator at the operator position 60 operates the ringing key back and forth between its normal and off-10 normal positions intermittently. When the party at the telephone substation C answers the call, a loop circuit is completed between the telephone instrument thereat and the battery supply relay R427 when the ringing key K430 is restored to its 15 normal position, this loop circuit extending from ground by way of the upper winding of R427 and the contacts 431 of the ringing key K430 to the plug tip 441 and from battery by way of the lower winding of R427 and the contacts 433 of the 20 ringing key K430 to the plug ring 442, the plug tip 441 and the plug ring 442 being included in the loop circuit extending to the telephone substation C as previously explained. When the loop circuit is completed between the telephone 25 instrument at the telephone substation C and the battery supply relay R427, the windings of the last-mentioned relay are energized, thereby to cause this relay to operate. Upon operating, the relay R427 interrupts at the contacts 428 a point 30 in the previously traced series circuit for illuminating the supervisory lamp L419 and for energizing the winding of the control relay R455, thereby to cause the supervisory lamp L419 to be 35 extinguished and the control relay R455 to restore. When the supervisory lamp L419 is extinguished, the operator at the operator position 60 is advised that the party at the telephone substation has answered the call. At this time, the 40 loop circuit extending between the telephone instrument A at the combination alarm and telephone station 50 and the battery supply relay R426 and the loop circuit extending between the telephone instrument at the telephone substation C and the battery supply relay R427 are operatively connected, the upper windings of the 45 relays R426 and R427 being connected together by way of the condenser 417 and the lower windings of the relays R426 and R427 being connected together by way of the condenser 418.
- 50 The operator at the operator position 60 may monitor the established connection between the combination alarm and telephone station 50 and the telephone substation C or she may disconnect from this established connection. In order to 55 disconnect from the established connection, the operator at the operator position 60 restores the keys K415 and K420 to their normal positions. When the key K420 is restored to its normal position, the previously traced series circuit for 60 energizing the windings of the control relays R470 and R480 is interrupted at the contacts 425 thereof and the previously traced circuit for energizing the winding of the control relay R458 is interrupted at the contacts 423 thereof, thereby to cause the last-mentioned relays to restore. Upon restoring, the control relays R470 and R480 65 interrupt the previously traced connections between the receiver 453 and the transmitter 454 and the repeater 410 by way of the repeater 495 and complete the previously traced connections between the receiver 453 and the transmitter 454 and the repeater 410 by way of the amplifiers 475 and 476. Upon restoring, the control relay R458 70 prepares at the contacts 459 a point in the pre- viously mentioned circuit for operating the alarm 444.
- When the conversation between the combination alarm and telephone station 50 and the telephone substation C is terminated, the parties thereat replace the receivers of the telephone instruments thereat upon their respective switchhooks, thereby to interrupt the previously traced loop circuits extending between the battery supply relays R426 and R427 and the telephone instruments at the station 50 and at the substation C, respectively, in order to cause the battery supply relays R426 and R427 to restore. Upon restoring, the relay R427 recompletes at the contacts 428 the previously traced series circuit for illuminating the supervisory lamp L419 and for energizing the winding of the control relay R455, thereby to cause the last-mentioned relay to operate. Upon operating, the relay R455 completes, at the contacts 456, the previously mentioned circuit for operating the alarm 444, this circuit extending from ground by way of the contacts 459, the contacts 456 and the winding of the alarm 444 to battery. The illumination of the supervisory lamp L419 and the operation of the alarm 444 indicate to the operator at the operator position 60 that the party at the telephone substation C has replaced the receiver of the telephone instrument thereat upon its switchhook. 30
- The operator at the operator position 60 may arrest the operation of the alarm 444 by re-operating the key K420 away from its normal position, thereby to complete the previously traced circuits for energizing the windings of the control relays R470, R480 and R458 in order to cause the last-mentioned relays to operate. Upon operating, the control relay R458 interrupts, at the contacts 459, the previously traced circuit for operating the alarm 444 and, upon 35 operating, the control relays R470 and R480 complete the previously traced circuits for operatively connecting the receiver 453 and the transmitter 454 to the repeater 410 by way of the repeater 495 as previously explained. At this time, 40 the operator at the operator position 60 may again converse with the party at the combination alarm and telephone station 50 in the event he has not replaced the receiver of the telephone instrument A thereat upon its switchhook. 45
- In the event the operator at the operator position 60 wishes to ringer the combination alarm and telephone station 50 in case the party thereat has replaced the receiver of the telephone instrument A upon its switchhook, the ringing key K405 is intermittently operated back and forth between its normal and off-normal positions. When the ringing key K405 is operated to its off-normal position, a circuit is completed for projecting ringing current over the line 100 to 50 the combination alarm and telephone station 50, this circuit extending from one terminal of a suitable source of alternating current supply by way of the contacts 407 of the ringing key K405, to the plug tip 402 and from the other terminal of the source of alternating current supply by way of the contacts 409 of the ringing key K405 to the plug ring 403, the plug tip 402 and the plug ring 403 being included in a circuit 55 extending by way of the line 100 to the combination alarm and telephone station 50. The alternating current thus projected over the line 100 to the station 50 causes the ringer thereat to be actuated in the event the receiver of the tele- 60
- 70
- 75

phone instrument A has been replaced upon its switchhook in the usual manner.

In order competely to release the established connection between the combination alarm and telephone station 50 and the telephone substation C, the operator at the operator position 60 withdraws the plugs P401 and P440 from the jacks J120 and J445, respectively terminating the lines 100 and 450. When the plug 402 is withdrawn from the jack J120, the previously traced circuit for energizing in series the upper winding of the control relay R435 and the answer relay R130 is interrupted, thereby to cause these relays to restore. Upon restoring, the control relay R435 10 interrupts at the contacts 438 a further point in the holding circuit for energizing the upper winding thereof, interrupts at the contacts 436 and 437 additional points in the previously traced connection between the plug P401 and the battery supply relay R426, and interrupts at the contacts 438 the previously traced series circuit for illuminating the supervisory lamp L419 and for energizing the winding of the control relay R455 in order to cause the supervisory lamp to be extinguished and the relay R455 to restore. Upon restoring, the answer relay R130 20 interrupts at the contacts 135 the previously traced alternative circuits for energizing the lower winding of the impulse relay R145, prepares at the contacts 134 a point in the previously traced holding circuit for energizing the winding of the control relay R150 and completes at the contacts 131 and at the contacts 132 the previously traced circuit for energizing the windings of the impulse relay R145 in series with the winding of the line relay R140. The impulse relay R145 remains in its operated position at this time. However, the line relay R140 remains restored, due to the high series resistance of the circuit for energizing the winding thereof, assuming that the party at the combination alarm and telephone station 50 has closed the door 52 of the enclosing casing 51 thereat, thereby to operate the door switch S113 in order to interrupt at the contacts 114 thereof the previously mentioned path for short-circuiting the resistor 108 as previously explained.

In order to initiate an alarm on one of the combination alarm and telephone lines, the door of the enclosing casing at the associated station 50 is opened and then the alarm switch thereat is operated. For example, in order to initiate an alarm on the combination alarm and telephone line 100, the party at the combination alarm and telephone station 50 opens the door 52 of the enclosing casing 51 thereat, thereby to cause the door switch S113 to be operated in order to complete at the contacts 114 thereof the previously mentioned path for short-circuiting the resistor 108. When the resistor 108 is thus short-circuited, the line relay R140 and the control relay R150 in the line circuit 189 individually associated with the combination alarm and telephone line 100 operate as previously explained, thereby to initiate a telephone call on the line 100 and 55 to cause the supervisory lamp L174 associated with the jack J120 at the operator position 60 to be steadily illuminated. The party at the station 50 then operates the alarm switch S115 momentarily, thereby to interrupt at the contacts 116 thereof the previously traced series circuit for energizing the winding of the line relay R140 and the windings of the impulse relay R145. Also, at the contacts 117 of the alarm switch S115, there is completed a path for short-circuiting the upper winding of the impulse relay

R145, this path extending from ground by way of the contacts 117 of the alarm switch S115, the contacts 114 of the door switch S113, the winding 107 of the repeater 105, the contacts 112 of the hookswitch S110, C101, the contacts 131, 5 C175 and the upper winding of R145 to ground. When the above-traced series circuit for energizing the windings of the impulse relay R145 is interrupted and the previously traced path for short-circuiting the upper winding of the impulse relay R145 is completed, the impulse relay R145 immediately restores to complete at the contacts 146 a circuit for energizing the winding of the control relay R160, this circuit extending from ground by way of the contacts 146, the 15 contacts 152, the winding of R160 and the resistor 124 to battery. When energized over the above-traced circuit, the relay R160 operates to complete at the contacts 161 an obvious holding circuit for energizing the winding thereof in 20 series with the resistor 124. It is noted that the alarm switch S115 at the combination alarm and telephone station 50 is only momentarily operated away from its normal position and then returned to its normal position, thereby to recomplete, at 25 the contacts 116 thereof, the previously traced series circuit for energizing the winding of the line relay R140 and the windings of the impulse relay R145. Accordingly, the impulse relay R145 re-operates and the line relay R140 operates in the 30 event that it has restored, the control relay R150 remaining operated due to the completed holding circuit for energizing the winding thereof. Upon reoperating, the impulse relay R145 interrupts at the contacts 146 a point in the previously traced original circuit for energizing the winding of the control relay R160, the latter relay remaining operated at this time due to the completed holding circuit for energizing the winding thereof.

It is noted that the alarm condition may be created upon the combination alarm and telephone line 100 by operating the alarm switch S115 regardless of whether the receiver of the telephone instrument A at the station 50 has been removed from its switchhook. In the event 45 the receiver of the telephone instrument A at the station 50 has been removed from its switchhook, operation of the alarm switch S115 completes, at the contacts 117 thereof, an alternative path for short-circuiting the upper winding of the impulse 50 relay R145, this circuit extending from ground at the contacts 117 of the alarm switch S115, the contacts 111 of the hookswitch S110, C104, the telephone instrument A, C103, C101, the contacts 131, C175 and the upper winding of the impulse 55 relay R145 to ground. Thus, the control relay R160 is operated incident to the operation of the alarm switch S115 regardless of whether the telephone instrument B or the telephone instrument A is employed at the station 50 to converse with 60 the operator at the operator position 60.

Also, upon operating, the control relay R160 65 interrupts at the contacts 163 the previously traced circuit for illuminating steadily the supervisory lamp L174 associated with the jack J120 at the operator position 60 and completes at the contacts 162 a circuit for illuminating intermittently the supervisory lamp L174. The last-mentioned circuit extends from interrupted ground potential appearing upon the control conductor C170 by way of the contacts 162 and the lamp L174 to battery. The flashing of the supervisory lamp L174 associated with the jack J120 at the operator position 60 indicates to the operator 70 thereat that an alarm condition is present upon 75

the combination alarm and telephone line 100. Accordingly, the operator at the operator position 60 answers the call on the line 100 immediately and in preference to other ordinary telephone calls waiting to be answered. The mode of answering the alarm call on the line 100 at the operator position 60 is the same as that previously explained. After the call has been answered at the operator position 60, the operator thereat may learn from the party at the combination alarm and telephone station 50 the nature of the emergency in the event the party remains at the station 50.

Also, upon operating, the control relay R160 in the line circuit 180 individually associated with the combination alarm and telephone line 100 completes at the contacts 164 and at the contacts 165 obvious paths for applying ground potential to the start conductor C172 and to the control conductor C171 respectively. The application of ground potential to the start conductor C172 and to the control conductor C171 initiates the operation of the finder sequence switch 304, thereby to cause the finder sequence switch 304 to select the particular finder switch 301 associated with the group of 200 lines including the line 100 having the alarm condition thereon. Subsequently, the selected finder switch 301 operates to select the line 100 in the associated group of 200 lines having the alarm condition thereon, whereupon the sender switch 305 operates to cause the recorder 307 to operate and make a record of the particular line 100 having the alarm condition thereon, thereby to identify the last-mentioned line. The sender sequence switch 306 causes the sender switch 305 to transmit the code to the recorder 307 a number of times; and thereafter the alarm recording equipment 300 is released and ground potential is applied to the control conductor C173.

The application of ground potential to the control conductor C173 completes a path for short-circuiting the winding of the control relay R160 in the line circuit 180 individually associated with the combination alarm and telephone line 100. This path extends from the grounded control conductor C173 to the upper terminal of the winding of the relay R160, the lower terminal of the winding of the relay R160 having ground potential connected thereto as previously noted. When the winding of the control relay R160 is thus short-circuited, this relay restores to interrupt at the contacts 161 a further point in the previously traced holding circuit for energizing the winding thereof, to interrupt at the contacts 162 the previously traced circuit for intermittently illuminating the supervisory lamp L174 associated with the jack J120 at the operator position 60, to prepare at the contacts 163 a point in the previously traced circuit for steadily illuminating the supervisory lamp L174, and to interrupt, at the contacts 164 and at the contacts 165, respectively, the previously mentioned paths for applying ground potential to the start conductor C172 and to the control conductor C171. At this time, the line circuit 180 individually associated with the combination alarm and telephone line 100 occupies its usually operated position to mark the line 100 as having a telephone call thereon. The line relay R140, the impulse relay R145 and the control relay R150 occupy their operated positions at this time, as previously noted.

The line circuit individually associated with each of the combination alarm and telephone lines is so connected and arranged that the su-

pervisory lamp associated with the jack terminating the line at the operator position 60 is illuminated in the event a fault appears upon the line. For example, the line circuit 180 individually associated with the combination alarm and telephone line 100 is so connected and arranged that the supervisory lamp L174 associated with the jack J120 terminating the line 100 at the operator position 60 is illuminated in the event the line 100 has an open circuit, a short circuit, or a ground circuit fault thereon. More particularly, in the event the line conductors C101 and C102 of the combination alarm and telephone line 100 are shorted together, an alternative circuit is completed for effectively energizing the winding of the line relay R140, this circuit extending from ground by way of the upper winding of the impulse relay R145, C175, the contacts 131, C101, the short circuit between C101 and C102, C102, the contacts 132, the winding of the line relay R140 and the lower winding of the impulse relay R145 to battery. When energized over the above-traced circuit, the line relay R140 operates to complete at the contacts 141 the previously mentioned circuit for energizing the winding of the control relay R150, thereby to cause the latter relay to operate. Upon operating, the control relay R150 completes, at the contacts 151, the previously traced holding circuit for energizing the winding thereof, and completes at the contacts 154 the previously traced circuit for steadily illuminating the supervisory lamp L174 associated with the jack J120 at the operator position 60.

Also, in the event either one of the line conductors C101 and C102 of the combination alarm and telephone line 100 is broken, the previously traced circuit for energizing in series the upper and lower windings of the impulse relay R145 is interrupted, thereby to cause the latter relay to restore. Upon restoring, the impulse relay R145 completes at the contacts 146 an alternative circuit for steadily illuminating the supervisory lamp L174 associated with the jack J120 at the operator position 60. The last-mentioned circuit extends from ground by way of the contacts 146, the contacts 153, the contacts 163 and the lamp L174 to battery.

Furthermore, in the event either the positive line conductor C101 or the negative line conductor C102 of the combination alarm and telephone line 100 is grounded, a circuit is completed for effectively energizing the winding of the line relay R140. The last-mentioned circuit extends from battery by way of the lower winding of the impulse relay R145, the winding of the line relay R140 and the contacts 132 to the line conductor C102. In the event the negative line conductor C102 is grounded, the last-mentioned circuit is completed directly; and, in the event the positive line conductor C101 is grounded, the last-mentioned circuit is completed by way of the contacts 116 of the alarm switch S115, the resistor 108, the winding 107 of the repeater 105 and the contacts 112 of the hookswitch S110 to the grounded positive line conductor C101. In either event the line relay R140 operates, thereby to cause the control relay R150 to operate and complete the previously traced circuit for steadily illuminating the supervisory lamp L174 associated with the jack J120 at the operator position 60 as previously explained.

When the supervisory lamp L174 associated with the jack J120 at the operator position 60 is illuminated, the operator thereat is advised

that a calling condition is present on the combination alarm and telephone line 100, whereupon she inserts the plug P401 of the cord circuit in the operator position apparatus 400 into the 5 jack J120 as previously explained. The operator at the operator position 60 then operates the key K420, thereby operatively to associate the receiver 453 and the transmitter 454 thereat with the line 100. At this time, the operator is unable to 10 converse over the combination alarm and telephone line 100 due to the fact that the call on this line has been created thereon by a faulty condition of the line as explained above. Accordingly, the operator at the operator position 60 15 tests the combination alarm and telephone line 100 to determine whether or not it is in working order. The line 100 is tested by inserting the plug P201 of the test circuit 200 into the jack J120 and then manipulating the keys associated 20 with the test circuit 200 in a manner more fully described hereinafter.

When the plug P201 of the test circuit 200 is inserted into the jack J120, a circuit is completed for energizing the winding of the answer relay 25 R130 in the line circuit 180 individually associated with the combination alarm and telephone line 100, this circuit extending from ground by way of the resistor 205, the plug sleeve 204, the jack sleeve 123, C176 and the winding of R130 30 to battery. When energized over the above-traced circuit, the answer relay R130 operates to interrupt at the contacts 131 and at the contacts 132 the previously traced circuit for energizing in series the winding of the line relay R140 35 and the windings of the impulse relay R145, and completes, at the contacts 133 and at the contacts 135, the previously traced circuit for energizing the winding of the line relay R140 in a reverse direction, thereby to cause the last- 40 mentioned relay to restore. Also, the answer relay R130 completes at the contacts 135 the previously traced holding circuit for energizing the lower winding of the impulse relay R145. Accordingly, at this time, the answer relay R130 and 45 the impulse relay R145 in the line circuit 180 occupy their operated positions while the line relay R140 and the control relay R150 in the line circuit 180 occupy their restored positions.

The operator at the operator position 60 checks 50 the operation of the ammeter 206 included in the test circuit 200 by operating the key K215 away from its normal position in one direction, thereby to complete at the contacts 223 and at the contacts 225 of the key K215 a test circuit for the ammeter 206. This test circuit extends from ground by way of the contacts 225 of the key K215, the winding of the ammeter 206, the resistor 226 and the contacts 223 of the key K215 55 to battery. Assuming that the ammeter 206 registers properly, the key K215 is returned to its normal position.

The operator at the operator position 60 then 60 operates the key K207 away from its normal position, thereby to complete a circuit for testing the condition of the line circuit 180. More particularly, a circuit is completed for testing whether or not the line 100 has been freed of impedance elements including the winding of the line relay R140 and the lower winding of the impulse relay R145. This test circuit extends from ground 65 by way of the contacts 203 of the key K207, the contacts 217 of the key K215, C230, the contacts 221 of the key K215, the contacts 224 of the key K215, the winding of the ammeter 206, the resistor 226, the contacts 222 of the key K215, 70

the contacts 219 of the key K215, C229, the contacts 214 of the key K210, the plug ring 203 and the jack ring 122 to the negative line conductor C102 of the line 100. In the event the line 100 has been freed of impedance elements including 5 the winding of the line relay R140 and the lower winding of the impulse relay R145 due to the proper operation of the answer relay R140, no potential appears upon the negative line conductor C102. Accordingly, the ammeter 206 does 10 not register any current flowing over the above-traced circuit. On the other hand, in the event the negative line conductor C102 of the line 100 has not been freed of impedance elements including the winding of the line relay R140 and 15 the lower winding of the impulse relay R145, due to the improper operation of the answer relay R130, battery potential appears upon the negative line conductor C102 of the line 100, this 20 battery potential being derived at the lower winding of the impulse relay R145. Accordingly, the ammeter 206 registers a current flowing over the above-traced circuit, thereby to indicate to the operator at the operator position 60 that the answer relay R130 in the line circuit 180 has not 25 operated to free the line 100 of impedance elements.

Assuming that the answer relay R130 in the line circuit 180 has operated properly as indicated, the operator at the operator position 60 30 then restores the key K207 to its normal position and operates the key K215 away from its normal position in the opposite direction, thereby to complete at the contacts 216 of the key K215 a path extending from ground by way of the contacts 216 of the key K215, the contacts 208 of the key K207 and the contacts 212 of the key K210 to the plug tip 202 and to complete at the contacts 218 of the key K215 a path extending from battery by way of the contacts 218 of the key K215, the contacts 222 of the key K215 and the resistor 226 to the negative terminal of the ammeter 206. When these paths are completed, the ammeter 206 fails to register any current in the event either of the line conductors C101 45 and C102 of the line 100 is interrupted. Also, in the event the line conductors C101 and C102 of the line 100 are shorted together, the ammeter 206 will register a high value of current. The circuit for causing the ammeter 206 to 50 register a high value of current extends from ground potential appearing on the plug tip 202 by way of the jack tip 121, C101, the shorted connection between C101 and C102, C102, the jack ring 122, the plug ring 203, the contacts 55 214 of the key K210, the contacts 220 of the key K215 and the contacts 224 of the key K215 to the positive terminal of the ammeter 206.

On the other hand, in the event either of the line conductors C101 and C102 of the line 100 is 60 grounded, the ammeter 206 will read some value of current flowing over a circuit including the line conductors of the line 100. In the present instance, ground potential is connected by way of the previously traced path to the plug tip 65 202 and battery potential is connected by way of the previously traced path including the ammeter 206 to the plug ring 203. Accordingly, at this time, if the positive line conductor C101 of the line 100 is grounded, the ammeter 206 70 will register a low value of current due to the fact that the resistor 108 at the combination alarm and telephone station 50 is included in the previously traced connection between the line conductors C101 and C102 of the line 100. On 75

the other hand, in the event the negative line conductor C102 of the line 100 is grounded, the ammeter 206 will register a high value of current due to the fact that the resistor 108 at the combination alarm and telephone station 50 is excluded from the circuit including the ammeter 206. In the event the ammeter 206 registers either a high value or a low value of current, the key K218 is operated. Upon operating the key K218, ground potential is applied to the plug ring 203 and battery potential is applied to the plug tip 202. The path for applying ground potential to the plug ring extends from ground by way of the contacts 216 of the key K215, the contacts 203 of the key K207, C228, and the contacts 213 of the key K110 to the plug ring 203; and the path for applying battery potential to the plug tip 202 extends from battery by way of the contacts 213 of the key K215, the contacts 222 of the key K215, the resistor 226, the winding of the ammeter 206, the contacts 224 of the key K215, the contacts 220 of the key K215, C227 and the contacts 211 of the key K210 to the plug tip 202.

With the key K210 operated, the ammeter 206 will register a high value of current in the event the positive line conductor C101 of the line 100 is grounded, due to the fact that the resistor 108 at the combination alarm and telephone station 50 is excluded from the path including the winding of the ammeter 206; while the ammeter 206 will register a low value of current in the event that the negative line conductor C102 of the line 100 is grounded, due to the fact that the resistor 108 at the combination alarm and telephone station 50 is included in the path including the winding of the ammeter 206. From the above, it will be understood that, by operating the key K210 back and forth while the key K215 is operated in the opposite direction away from its normal position, the particular one of the line conductors C101 or C102 of the line 100 which is grounded may be determined by the operator at the operator position 60.

Assuming that one of the line conductors C101 or C102 of the combination alarm and telephone line 100 is grounded, the operator at the operator position 60 first determines which one of the line conductors is grounded and then establishes a connection between the defective line 100 and one of the correcting circuits, such, for example, as the correcting circuit 245, by utilizing one of the patching cords, such, for example, as the patching cord 231. First, the operator at the operator position 60 inserts the plug P235 of the patching cord 231 into the jack J120 and then inserts the plug P240 of the patching cord 231 into one of the jacks J246 or J251 of the correcting circuit 245 depending upon which one of the line conductors of the combination alarm and telephone line 100 is grounded. In the event the positive line conductor C101 of the line 100 is grounded, the plug 240 of the patching cord 231 is inserted into the jack J251. On the other hand, in the event the negative line conductor C102 of the line 100 is grounded, the plug 240 of the patching cord 231 is inserted into the jack J246.

Assuming that the negative line conductor C102 of the combination alarm and telephone line 100 is grounded, the plugs P235 and P240 of the patching cord 231 are inserted into the jacks J120 and J246, respectively. When the plug P240 is inserted into the jack J246, an obvious path is completed at the contacts 250 of the jack J246.

for energizing the winding of the control relay R265, thereby to cause the latter relay to operate. Also, when the plug P240 is inserted into the jack J246, a circuit is completed for energizing the winding of the answer relay R130 in the line circuit 180 individually associated with the combination alarm and telephone line 100. The last-mentioned circuit extends from ground by way of the contacts 286, the resistor 244, C292, the jack sleeve 249, the plug sleeve 241, C232, the 10 plug sleeve 236, the jack sleeve 123, C176 and the winding of R130 to battery. When energized over the above-traced circuit, the answer relay R130 operates as previously explained, thereby to cause the impulse relay R145 to remain in its operated 15 position and the line relay R140 to restore. Upon restoring, the line relay R140 interrupts the previously traced circuit for energizing the winding of the control relay R150 in the event the last-mentioned relay is operated. Accordingly, at this 20 time the circuit for steadily illuminating the lamp L174 associated with the jack J120 at the operator position 60 is interrupted. Finally, when the plug P240 is inserted into the jack J246, a circuit is completed for energizing the winding of the 25 control relay R270 in the correcting circuit 245, this circuit extending from ground by way of the jack ring 248, the plug ring 242, C233, the plug ring 237, the jack ring 122, C162, the contacts 116 of the alarm switch S115, the resistor 108, the 30 winding 107 of the repeater 105, the contacts 112 of the hook switch S110, C101, the jack tip 121, the plug tip 238, C234, the plug tip 243, the jack tip 247, the contacts 262, the contacts 266, the contacts 271 and the winding of R270 to battery. 35 It is noted that direct ground potential at the jack ring 248 is applied to the grounded negative line conductor C102 of the line 100 and that the above-traced circuit for energizing the winding of the control relay R270 in the correcting circuit 40 245 includes the resistor 108. Accordingly, the control relay R270 in the correcting circuit 245 does not operate at this time due to the high series resistance of the circuit for energizing the winding thereof.

At this time, the defective combination alarm and telephone line 100 has been rendered operative by utilizing the correcting circuit 245, which circuit is utilized in connection with the line 100 until the negative line conductor C102 of the line 50 100 is cleared of the grounding fault thereon.

At this time a telephone call may be initiated on the line 100 in the usual manner by opening the door 52 of the enclosing casing 51 at the combination alarm and telephone station 50 as previously 55 explained, thereby to complete at the contacts 114 of the door switch S113 the previously mentioned path for short-circuiting the resistor 108. When the resistor 108 is thus short-circuited, the resistance of the previously traced circuit for energizing the winding of the control relay R270 is appreciably reduced, thereby to cause the last-mentioned relay to be effectively energized, whereupon it operates. Upon operating, relay R270 interrupts at the contacts 271 a point in a 60 circuit, traced hereinafter, for energizing the winding of the relay R280 and completes at the contacts 272 a circuit for energizing the winding of the control relay R275, this circuit extending from ground by way of the contacts 264, the contacts 268, the control conductor C293, the contacts 272 and the winding of R275 to battery. When energized over the above-traced circuit, the relay R275 operates to complete at the contacts 276 a 65 obvious holding circuit for energiz- 70 75

ing the winding thereof by way of the grounded control conductor C293, prepares at the contacts 276 a further point in the previously mentioned circuit for energizing the winding of the control circuit for energizing the winding of the control relay R280 and interrupts at the contacts 277 an obvious path for short-circuiting the resistor 273, thereby to cause the resistor 273 to be inserted in series in the previously traced circuit for energizing the winding of the control relay R270. When the resistor 273 is inserted into the circuit for energizing the winding of the control relay R270, the last-mentioned relay remains in its operated condition. However, it is rendered extremely fast to restore in the event the circuit for energizing the winding thereof is momentarily interrupted. Also, upon operating, the control relay R275 completes at the contacts 278 a circuit for steadily illuminating the supervisory lamp L256 individually associated with the connecting circuit 245, this circuit extending from ground by way of the contacts 284, the contacts 278 and the lamp L256 to battery. The steady illumination of the lamp L256 indicates to the operator at the operator position 60 that a telephone call has been initiated on the combination alarm and telephone line 100 associated with the correcting circuit 245.

The operator at the operator position 60 answers the call by inserting the plug P401 of the cord circuit in the operator position apparatus 400 into the jack J251. When the plug P104 is inserted into the jack J251, an obvious circuit is completed at the contacts 255 of the jack P251 for energizing the winding of the control relay R260, thereby to cause the latter relay to operate. Upon operating, the control relay R260 interrupts at the contacts 264 a point in the previously traced holding circuit for energizing the winding of the control relay R275, thereby to cause the latter relay to restore and interrupt at the contacts 278 the previously traced circuit for steadily illuminating the supervisory lamp L256. Also, upon operating, the control relay R260 interrupts at the contacts 262 a point in the previously traced circuit for energizing the winding of the control relay R270, thereby to cause the latter relay to restore.

Also, when the plug P401 is inserted into the jack J251, the repeater 410 included in the operator position apparatus 400 is operative associated with the repeater 105 at the combination alarm and telephone station 50, assuming that the key K420 has been operated away from its normal position. The circuit for operatively associating the repeaters 410 and 105 extends from ground by way of the jack ring 248, the plug ring 242, C233, the plug ring 237, the jack ring 122, C102, the contacts 116 of the alarm switch S115, the contacts 114 of the door switch S113, the winding 107 of the repeater 105, the contacts 112 of the hook switch S110, C101, the jack tip 121, the plug tip 238, C234, the plug tip 243, the jack tip 247, the jack ring 253, the plug ring 403, the contacts 408 of the ringing key K405 and the contacts 422 of the key K420 to the lower terminal of the winding 414 of the repeater 410 and from ground by way of the jack tip 252, the plug tip 402, the contacts 406 of the ringing key K405, and the contacts 421 of the key K420 to the upper terminal of the winding 413 of the repeater 412.

After the operator at the operator position 60 answers the call as previously described, the call may be extended to one of the telephone stations as previously explained. In order to

extend the call to one of the telephone stations, the key K415 is operated, thereby to cause the control relay R435 to operate as previously noted. Upon operating, the relay R435 completes at the contacts 438 a holding circuit for energizing the upper winding thereof in series with the winding of the answer relay R130 in the line circuit 180. The last-mentioned circuit extends from ground by way of the upper winding of the relay R435, the contacts 438, the plug sleeves 404, the jack 10 sleeve 254, the jack sleeve 249, the plug sleeve 241, C232, the plug sleeve 236, the jack sleeve 123, C176 and the winding of R130 to battery. Also upon operating, the control relay R435 completes at the contacts 431 a loop circuit for supplying battery current to the common battery telephone instrument A at the combination alarm and telephone station 50, this circuit extending from the grounded line conductor C102 of the line 100 by way of the contacts 116 of the alarm switch S115, the contacts 111 of the hookswitch S110, C104, the telephone instrument A, C103, C101, the jack tip 121, the plug tip 238, C234, the plug tip 243, the jack tip 247, the jack ring 253, the plug ring 403, the contacts 408 of the ringing key K405, the contacts 431 and the lower winding of R426 to battery. The extension of the connection over the telephone line extending to the telephone substation, and the release of the established connection between the telephone substation and the combination alarm and telephone station 50 are the same as those previously explained.

Furthermore, it is noted that an alarm may be initiated on the combination alarm and telephone line 100 at the combination alarm and telephone station 50 while the line 100 is operatively associated with the correcting circuit 245 as previously explained. At this time, the answer relay R130 and the impulse relay R145 in the line circuit 180 individually associated with the combination alarm and telephone line 100 occupy their operated positions. Also, when the answer relay R130 operates, it completes at the contacts 136 an obvious circuit for energizing the control relay R190 in the line circuit 180, thereby to cause the latter relay to operate. Furthermore, the answer relay R130 interrupts at the contacts 137 a point in a circuit, traced hereinafter, for energizing the winding of the control relay R185 in the line circuit 180. At this time, only the control relay R265 in the correcting circuit 245 occupies its operated position.

When the party at the combination alarm and telephone set 50 opens the door of the enclosing casing thereat, the previously traced circuit for effectively energizing the winding of the control relay R270 in the correcting circuit 245 is completed, thereby to cause the latter relay to operate and complete the previously traced circuit for energizing the winding of the control relay R275. The control relay R275 then operates as previously explained. The party at the combination alarm and telephone station 50 then momentarily operates the alarm switch S115 as previously explained, thereby to interrupt at the contacts 116 thereof the previously traced circuit for energizing the winding of the control relay R270, whereupon the latter relay restores. Upon restoring, the relay R270 completes, at the contacts 271, the previously mentioned circuit for energizing the winding of the control relay R280, this circuit extending from the grounded control conductor C293, by way of

the contacts 271, the contacts 276 and the winding of R280 to battery. When energized over the above-traced circuit, the relay R280 operates to complete at the contacts 281 an obvious holding circuit for energizing the winding thereof by way of the grounded control conductor C293 and interrupts at the contacts 284 a point in the previously traced circuit for steadily illuminating the lamp L256. Also the relay R280 completes at the contacts 283, a circuit for intermittently illuminating the supervisory lamp L256, this circuit extending from interrupted ground potential appearing upon the control conductor C257 by way of the contacts 283, the contacts 278 and the lamp L256 to battery. The flashing of the supervisory lamp L256 indicates to the operator at the operator position 60 that the combination alarm and telephone line 100 operatively associated with the correcting circuit 245 has an alarm condition thereon. Also, upon operating, the control relay R290 interrupts at the contacts 286 a point in the previously traced circuit for energizing the winding of the answer relay R130 in the line circuit 180 individually associated with the combination alarm and telephone line 100, thereby to cause the latter relay to restore. Further, the relay R280 prepares at the contacts 285 a point in an alternative circuit, traced hereinafter, for energizing the winding of the answer relay R130 and completes at the contacts 282 an obvious circuit for energizing the winding of the control relay R290. Shortly after the winding of the control relay R290 is energized over the previously mentioned circuit, this relay operates, as it is of the slow-to-operate type, and completes at the contacts 291 the previously mentioned alternative circuit for energizing the winding of the answer relay R130. The last-mentioned circuit extends from ground by way of the contacts 285, the contacts 291, the resistor 244, the jack sleeve 249, the plug sleeve 241, C232, the plug sleeve 286, the jack sleeve 123, C176 and the winding of R130 to battery. When energized over the above-traced circuit, the answer relay R130 reoperates. From the foregoing it is apparent that, incident to the operation of the alarm switch S115 at the combination alarm and telephone station 50, the correcting circuit 245 operatively associated with the alarm and telephone line 100 causes the answer relay R130 in the line circuit 180 to restore and then reoperate. When the answer relay R130 restores, it completes at the contacts 137 the previously mentioned circuit for energizing the winding of the control relay R185, this circuit extending from ground by way of the contacts 137, the contacts 191 and the winding of R185 to battery. When energized over the above-traced circuit, the relay R185 operates to prepare at the contacts 186 a point in a circuit, traced hereinafter, for energizing the winding of the control relay R160. When the answer relay R130 reoperates, it completes, at the contacts 188, the previously mentioned circuit for energizing the winding of the control relay R160, this circuit extending from ground by way of the contacts 186, the contacts 192, the contacts 188, the winding of R160 and the resistor 124 to battery. When energized over the above-traced circuit, the relay R160 operates and completes at the contacts 161 the previously traced holding circuit for energizing the winding thereof. Furthermore, upon operating, the relay R160 causes the alarm recording equipment 300 to be operated, whereupon the recorder

307 is operated to make a record identifying the combination alarm and telephone line 100 having an alarm condition thereon as previously explained.

It is noted that the control relays R185 and R190 are of the slow-to-release type. Accordingly, these relays remain operated during the time interval required for the answer relay R130 to restore and again reoperate, due to the fact that this time interval is very short. Shortly 10 after the answer relay R130 reoperates, the control relay R185 restores as the circuit for energizing the winding thereof is interrupted at the contacts 137, upon reoperation of the answer relay R130. Upon restoring, the control relay 15 R185 interrupts at the contacts 186 the previously traced original circuit for energizing the winding of the control relay R160. The operator at the operator position 60 then answers the call by inserting the plug P401 of the cord circuit in the operator position apparatus 400 into the jack J251 as previously explained. When the plug P401 is inserted into the jack J251, the previously traced circuit for energizing the winding of the control relay R280 is completed, thereby to cause the last-mentioned relay to operate and remove ground potential from the conductor C293. When ground potential is removed from the control conductor C293, the previously traced holding circuits for energizing the windings of the control relays R275 and R280 are interrupted, thereby to cause the latter relays to restore. Upon restoring, the control relay R280 recomplete at the contacts 280 the original circuit for energizing the winding of the answer relay R130, thereby to prevent the last-mentioned relay from restoring at this time. Also, upon restoring, the control relay R280 interrupts, at the contacts 282, the previously mentioned circuit for energizing the winding of the control relay R290, thereby to cause the latter relay to restore. Upon restoring, the control relay R275 interrupts at the contacts 278 the previously traced circuit for illuminating the supervisory lamp L256. In order to release the established connection between the combination alarm and telephone station 50 and the operator position 60, the operator thereat withdraws the plug P401 from the jack J251 as previously explained.

It is noted that, when the combination alarm and telephone line 100 has been cleared of faults, the connection between this line and the correcting circuit 245 is interrupted by withdrawing the plugs P235 and P240 of the patching cord 231 from the respective jacks J120 and J246. When the plug P235 is withdrawn from the jack J120, the previously traced circuit for energizing the winding of the answer relay R130 is interrupted, thereby to cause the latter relay to restore. Upon 40 restoring, the answer relay R130 completes at the contacts 137 the previously traced circuit for energizing the winding of the control relay R185, thereby to cause the latter relay to operate while the control relay R190 occupies its 45 operated position. Shortly thereafter, the control relay R190 restores and interrupts at the contacts 191 the previously traced circuit for energizing the winding of the control relay R185, whereupon the last-mentioned relay restores 50 shortly thereafter. Accordingly, the removal of the plug P235 from the jack J120 does not cause the control relay R160 in the line circuit 180 to operate at this time.

In the foregoing description of the opera- 75

tion of the correcting circuit 245 in conjunction with the defective combination alarm and telephone line 100, the plug P240 of the patching cord 231 was inserted into the jack J246 due to the fact that it was assumed that the negative line conductor C102 of the line 100 had a ground fault thereon. In the event the positive line conductor C101 of the combination alarm and telephone line 100 had a ground fault thereon, the plug P240 of the patching cord 231 would be inserted into the jack J251 after the plug 235 of the patching cord 231 is inserted into the jack J120 terminating the line 100. The operations of the correcting circuit 245 in conjunction with the combination alarm and telephone line 100 under these conditions are substantially the same as the operations thereof under the conditions more fully described above. Accordingly, in the interest of brevity, the details of the operations of the correcting circuit 245 in conjunction with the combination alarm and telephone line 100 under these conditions are omitted.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a station provided with an enclosing casing having a door, a line extending to said station and connected to a source of current, telephone apparatus housed in said casing, a resistor at said station, said telephone apparatus and said resistor being normally connected in series circuit relationship in said line, the resistance of said resistor being so proportioned that said telephone apparatus is normally effectively deenergized, a switch at said station operative to reduce the effective resistance of said resistor, thereby effectively to energize said telephone apparatus, means controlled when the effective resistance of said resistor is reduced for initiating a telephone call on said line, and means controlled by the door of said casing for operating said switch.

2. In a telephone system, a station provided with an enclosing casing having a door, a line extending to said station and connected to a source of current, a repeater and a resistor at said station, said repeater and said resistor being normally connected in series circuit relationship in said line, the resistance of said resistor being so proportioned that said repeater is normally effectively deenergized, a telephone instrument housed in said casing and operatively associated with said repeater, a switch at said station operative to short-circuit said resistor, thereby effectively to energize said repeater, means controlled when said resistor is short-circuited for initiating a telephone call on said line, and means controlled by the door of said casing for operating said switch.

3. In a telephone system, a station provided with an enclosing casing having a door, a line extending to said station and connected to a source of current, a repeater at said station normally operatively disassociated from said line, a first telephone instrument of the sound-powered type housed in said casing and operatively associated with said repeater, a second telephone instrument of the common battery type housed in said casing and normally operatively disassociated from

said line, means controlled by the door of said casing for operatively associating said repeater with said line, means including a hook switch housed in said casing for operatively associating said second telephone instrument with said line, and means controlled when said repeater or said second telephone instrument is operatively associated with said line for initiating a telephone call on said line. 5

4. In a telephone system, a station provided with an enclosing casing having a door, a line extending to said station and connected to a source of current, a repeater at said station provided with first and second windings, a first telephone instrument of the sound-powered type housed in 15 said casing and operatively associated with the first winding of said repeater, the second winding of said repeater being normally operatively disassociated from said line, a second telephone instrument of the common battery type housed in 20 said casing and normally operatively disassociated from said line, means controlled when the door of said casing is opened for operatively associating the second winding of said repeater with said line, means including a hookswitch housed in 25 said casing and operative to short-circuit the second winding of said repeater and operatively to associate said second telephone instrument with said line, and means controlled when the second winding of said repeater or said second telephone 30 instrument is operatively associated with said line for initiating a telephone call on said line.

5. In a signaling system, a station, an operator position, a line extending between said station and said operator position and connected to a source of current, telephone apparatus at said station and adapted to be operatively associated with said line, answering apparatus at said operator position and adapted to be operatively associated with said line, a line circuit associated with said line 35 and including first and second relays, a resistor at said station, said first relay, said second relay and said resistor being connected in series circuit relationship in said line, said first relay being normally operated and said second relay being 40 normally restored, means at said station for reducing the effective resistance of said resistor, thereby to cause said second relay to operate, means at said station for interrupting said line, thereby to cause said first relay to restore, means 45 responsive to the restoration of said first relay or the operation of said second relay for transmitting a first signal to said operator position, and means responsive to the restoration of said first relay following the operation of said second 50 relay for transmitting a second signal to said operator position.

6. In a telephone system, a station provided with an enclosing casing having a door, a line extending to said station and connected to a source of current, telephone apparatus housed in said casing and adapted to be operatively associated with said line, answering apparatus at said operator position and adapted to be operatively associated with said line, a line circuit associated with 60 said line and including first and second relays, a resistor at said station, said first relay, said second relay and said resistor being connected in series circuit relationship in said line, said first relay being normally operated and said second 65 relay being normally restored, means controlled by the door of said casing for reducing the effective resistance of said resistor, thereby to cause said second relay to operate, means including a device housed in said casing for interrupting said 70

line, thereby to cause said first relay to restore, means responsive to the restoration of said first relay or the operation of said second relay for transmitting a first signal to said operator position, and means responsive to the restoration of said first relay following the operation of said second relay for transmitting a second signal to said operator position.

7. In a signaling system, a station, an operator position, a line extending between said station and said operator position and connected to a source of current, telephone apparatus at said station and adapted to be operatively associated with said line, answering apparatus at said operator position and adapted to be operatively associated with said line, a line circuit associated with said line and including first and second relays, a resistor at said station, said first relay, said second relay and said resistor being connected in series circuit relationship in said line, said first relay being normally operated and said second relay being normally restored, means at said station for reducing the effective resistance of said resistor, thereby to cause said second relay to operate, means at said station for interrupting said line, thereby to cause said first relay to restore, means responsive to the operation of said second relay for initiating a telephone call on said line, and means responsive to the restoration of said first relay following the operation of said second relay for initiating an alarm on said line.

8. In a signaling system, a station, an operator position, a line extending between said station and said operator position, said line being subjected to ground faults, telephone apparatus at said station and adapted to be operatively associated with said line, means at said station for initiating a telephone call on said line, means at said station for initiating an alarm on said line, a line circuit normally associated with said line, a correcting circuit adapted to be associated with said line when said line has a ground fault thereon, means controlled from said operator position for disassociating said line circuit from said line and for associating said correcting circuit with said line, means included in each of said circuits and responsive to the presence of a telephone call on said line when the circuit is associated therewith for transmitting a first signal to said operator position, and means included in each of said circuits and responsive to the presence of an alarm on said line when the circuit is associated therewith for transmitting a second signal to said operator position.

9. In a signaling system, a station, an operator position, a line extending between said station and said operator position, said line being subjected to ground faults, telephone apparatus at said station and adapted to be operatively associated with said line, means at said station for initiating a telephone call on said line, means at said station for initiating an alarm on said line, a line circuit normally associated with said line, a correcting circuit adapted to be associated with said line when said line has a ground fault thereon, means controlled from said operator position for disassociating said line circuit from said line and for associating said correcting circuit with said line, means included in each of said circuits and responsive to the presence of a telephone call on said line when the circuit is associated therewith for transmitting a first signal to said operator position, means operative to identify said line, and means included in each of said circuits

and responsive to the presence of an alarm on said line when the circuit is associated therewith for transmitting a second signal to said operator position and for controlling the operation of said last-mentioned means.

10. In a signaling system, a station, an operator position, a line extending between said station and said operator position, said line being subjected to ground faults, telephone apparatus at said station and adapted to be operatively associated with said line, means at said station for initiating a telephone call on said line, means at said station for initiating an alarm on said line, a line circuit normally associated with said line, a correcting circuit adapted to be associated with said line when said line has a ground fault thereon, means controlled from said operator position for disassociating said line circuit from said line and for associating said correcting circuit with said line, a relay, means included in each of said circuits and responsive to the presence of an alarm on said line when the circuit is associated therewith for controlling the operation of said relay, means operative to identify said line, and means including said relay for controlling the operation of said last-mentioned means.

11. In a signaling system, a station provided with an enclosing casing having a door, an operator position, a line extending between said station and said operator position, said line being subjected to ground faults, telephone apparatus housed in said casing and adapted to be operatively associated with said line, a device housed in said casing, a line circuit normally associated with said line, a correcting circuit adapted to be associated with said line when said line has a ground fault thereon, means controlled from said operator position for disassociating said line circuit from said line and for associating said correcting circuit with said line, a relay, means included in each of said circuits and responsive to the opening of the door of said casing and the subsequent operation of said device when the circuit is associated with said line for controlling the operation of said relay, means operative to identify said line, and means including said relay for controlling the operation of said last-mentioned means.

12. In a signaling system, a station provided with an enclosing casing having a door, an operator position, a line extending between said station and said operator position, said line being subjected to ground faults, telephone apparatus housed in said casing and adapted to be operatively associated with said line, a device housed in said casing, a line circuit normally associated with said line, a correcting circuit adapted to be associated with said line when said line has a ground fault thereon, means controlled from said operator position for disassociating said line circuit from said line and for associating said correcting circuit with said line, a relay individual to said line, means included in each of said circuits and responsive to the opening of the door of said casing and the subsequent operation of said device when the circuit is associated with said line for causing said relay to operate, means operative to identify said line, and means responsive to the operation of said relay for marking said line to be identified and for controlling the operation of said last-mentioned means.
